United States Patent Office

Des. 180,644
Patented July 16, 1957

180,644

COMBINED COMB AND BRUSH RACK

Henry B. Flockner, Los Angeles, Calif.

Application October 17, 1956, Serial No. 43,382

Term of patent 14 years

(Cl. D86—10)

Fig. 1

Fig. 2

Fig. 1 is a front view of a combined comb and brush rack embodying my new design;

Fig. 2 is a side view thereof;

Fig. 3 is a back view on a reduced scale;

Fig. 4 is a top plan view also on a reduced scale, and

Fig. 5 is a bottom view thereof on said reduced scale.

The dotted line showing in Figs. 1 and 2 of the drawing is for illustrative purposes only.

I claim:

The ornamental design for a combined comb and brush rack, substantially as shown and described.
